UNITED STATES PATENT OFFICE.

THOMAS F. BYRON, OF CHICAGO, ILLINOIS.

CURTAIN ROD.

Application filed September 29, 1924. Serial No. 740,537.

To all whom it may concern:

Be it known that I, THOMAS F. BYRON, a citizen of the United States, residing at Chicago, in the county of Cook and State 5 of Illinois, have invented a new and useful Improvement in Curtain Rods, of which the following is a specification.

This invention relates to curtain rods and the like and is fully described in the following specification and shown in the accompanying drawing in which:

Figure 1 is a partial perspective view of a set of triple rods embodying the invention;

Fig. 2 is a section through one of the rods on the line 2 of Fig. 1;

Fig. 3 is a perspective view of the same before it is bent;

Fig. 4 is a perspective view of a reinforcing metal filler strip;

Fig. 5 is an edge view of the preferred form of notch;

Fig. 6 is a front elevation of the same;

Fig. 7 is a view similar to Fig. 3 showing a modified form of the notch;

Fig. 8 is an edge view of the rod shown in Fig. 7; and

Fig. 9 is a front elevation of the same.

The device illustrated in Figs. 1 to 6 inclusive comprises a flat sheet metal member 10 rolled or otherwise formed, rolled into a flat C-shape as shown in Fig. 2. This is provided with a series of notches 11, 12, 13, 14, 15 and 16 which extend transversely 30 across the rod as shown in Figs. 5 and 6. In this form they are completely cut from the inner portions of the rod so that it can readily be bent substantially at right angles as shown in Fig. 1 at any one of 35 the points where the notches occur.

The result is that these rods may all be made alike, except for the fact that the rods 10^a are made smaller than the rods 10 so that they may telescope therein. This 45 permits these rods to be carried in stock by the retailer in the straight form and he can readily bend them in the completed form as the individual customer requires them.

This means a very great saving in the 50 manner of cartons since it will readily be seen that the carton carried to contain three curtain rods bent in the form shown in Fig. 1, is very much larger, costlier and

takes up much more space than would the carton which would be carried to enclose an equal number as shown in Fig. 3.

Moreover, it will readily be apparent that a very much smaller number of cartons will be required for the reason that two notched rods 10 and 10^a by being bent at different notches may be made to serve the purpose of a great many different sizes of curtain rods as shown in Fig. 1, all of which would otherwise have to be carried in stock complete when they are bent at the factory as is now the customary practice in the manufacture of such rods.

In Figs. 7, 8 and 9, I have shown a modified form of rod 17 in which the notches 18, 19 and the like are placed or clamped in from the inner side of the rod instead of being cut through as in Figs. 1 to 6.

In Figs. 1, 2 and 4 is shown a flat metal strip 20 which may readily be inserted into the hollow rod 10 by being flat therein from the end. This is so placed as to lie on each side of the bend so that after the bend is made it serves as a reinforcing member for the curtain or bend.

As is well known in the art these curtain rods may be put up as a single rod, double for the use of a curtain or a valance, or triple for carrying a curtain or drape and valance. The latter is the form shown in Fig. 1 where there are three parallel rods all carried by a single bracket 21 at each end.

It will also be readily apparent that this arrangement permits three or more of the rods 10 and 10^a to be arranged in an alternate series of large and small rods, only the end rods being bent in to receive the brackets.

While I have described and shown by a few embodiments it is to be understood that it is capable of many modifications. Changes therefore in the construction and arrangement may be made which do not depart from the spirit and scope of the invention as disclosed in the appended 100 claims.

I claim:

1. A metallic curtain rod of flat C-shaped cross-section having a plurality of spaced notches formed near one end of said rod in the open sides of the C to facilitate the 105

bending of said rod whereby said rod can readily be selectively bent at any one of a plurality of points to provide an angular extension.

5. 2. A curtain rod of flat C-shaped cross-section having a plurality of spaced notches cut from the open sides of the C to facilitate the bending of said rod near its ends

to form angular supports therefor, whereby said rod can readily be selectively bent at any one of a plurality of points to provide an angular extension, and a metal strip adapted to be placed in said rod previous to bending for reinforcing said bend.

THOMAS F. BYRON.
